(57) **CLAIM**

I claim the ornamental design for a pair of makeup cases, as shown and described.

DESCRIPTION

FIG. 1 is an exploded rear perspective view of a pair of makeup cases, showing my new design;

FIG. 2 is an exploded front perspective view thereof;

FIG. 3 is an exploded front elevational view thereof;

FIG. 4 is an exploded rear elevational view thereof;

FIG. 5 is an exploded top plan view thereof;

FIG. 6 is an exploded bottom plan view thereof;

FIG. 7 is an exploded right-side elevational view thereof;

FIG. 8 is a left-side elevational view thereof;

FIG. 9 is a front perspective view thereof;

FIG. 10 is a rear perspective view thereof;

FIG. 11 is a front elevational view thereof;

FIG. 12 is a rear elevational view thereof;

FIG. 13 is a top plan view thereof;

FIG. 14 is a bottom plan view thereof;

FIG. 15 is a right-side elevational view thereof; and,

FIG. 16 is a left-side elevational view thereof.

The broken lines in the drawings represent portions of the pair of makeup cases that form no part of the claimed design.

1 Claim, 14 Drawing Sheets
